UNITED STATES PATENT OFFICE.

FRED T. HARRIGAN, OF TURNERS FALLS, MASSACHUSETTS.

HASP-FASTENER.

1,087,763.

Specification of Letters Patent.

Patented Feb. 17, 1914.

Application filed July 22, 1913. Serial No. 780,508.

To all whom it may concern:

Be it known that I, FRED T. HARRIGAN, a citizen of the United States, residing at Turners Falls, in the county of Franklin 5 and State of Massachusetts, have invented new and useful Improvements in Hasp-Fasteners, of which the following is a specification.

This invention is an improved hasp fastener for use on doors which are fastened by means of padlocks, the object of the invention being to provide an improved hasp fastener in which the heads of the securing screws are covered so that surreptitious removal of the hasp or of the staple plate is prevented and hence a door provided with my improved hasp fastener cannot be opened without leaving evidence of such fact, the invention consisting in the construction, 20 combination and arrangement of devices hereinafter described and claimed.

In the accompanying drawings: Figure 1 is a front elevation of my improved hasp fastener showing the hasp engaged with a staple and ready for the insertion of the shackle of the lock in the staple, the lock with its shackle being indicated in dotted lines. Fig. 2 is a longitudinal horizontal sectional view of the same. Fig. 3 is a detail elevation of the attaching plate of the hasp. Fig. 4 is a detail vertical transverse view taken on the plane indicated by the line *a—a* of Fig. 1. Fig. 5 is a detail elevation of the staple plate and its staple.

In accordance with my invention I provide an attaching plate 1 which corresponds in size and shape with the fixed member 2 of the hasp and is here shown as of oblong rectangular form provided with a central opening 3 and also with securing screw receiving openings 4 near its corners. At the lower inner corner the said attaching plate is provided with an outstanding horizontally arranged flange 5. This attaching plate 25 is in practice secured by means of screws in the openings 4 to a jamb or wall at one side of a door opening, as indicated in Figs. 1 and 2. The staple plate 6 is also secured by screws or the like to the door, at a suitable point, and is provided in its corners with openings 7 for the reception of the securing screws, the staple being indicated at 50 8 and being here shown as arranged across the center of the staple plate.

The hasp comprises, in addition to the fixed plate 2, a member 9 which is hinged

as at 10 to one end of the plate 2 or fixed member, and the said hinged or pivoted member 9 which is adapted to coact with the staple plate and staple has an opening 60 11 to clear the staple and permit the latter to project through said opening when the hasp member 9 is closed against the outer side of the staple plate.

The fixed member 2 of the hasp, after the attaching plate has been secured to the wall or jamb is placed on the outer side of said attaching plate, so as to cover the same and to bear on the flange 5 and is then permanently and pivotally secured to the attaching plate by means of a rivet 12 which is arranged and headed in the central opening 3 of the attaching plate, and in a similar opening 13 with which the said fixed plate or member of the hasp is provided. 70 It will be observed and understood that when the plate 2 has been thus secured to the attaching plate it serves to cover and conceal the attaching plate and to cover and bear on the heads of the securing screws so as to prevent the securing screws from being removed excepting by first either bending the fixed covering plate 2 out of the way or else drawing the rivet, either of which operations will so mar and injure the plate 80 2 as to clearly betray the fact that the hasp has been tampered with.

The pivoted member 9 of the hasp corresponds in size and shape with the staple plate 6 and when it is closed over said staple 90 plate and the opening 11 is engaged by the staple, the said hasp member 9 completely covers the staple plate and the heads of the screws in the opening 7 and hence prevents the screws from being removed and the 95 staple plate from being detached while the hasp is secured to the staple plate by a padlock. But when the hasp is turned on the pivot rivet 12 so that the plate 2 is at right angles to plate 1 the screw heads are uncovered. Hence installation and removal 100 of the hasp when desired are facilitated. The flange 5 by engaging the end of the plate normally holds the hasp in horizontal operative position.

My improved hasp is adapted to be used on freight car doors and also on the doors of other structures and effectually prevents surreptitious opening of such door.

I claim:

The herein described hasp comprising a relatively fixed member and a movable

110

member pivotally connected thereto, said movable member having a staple receiving slot, in combination with an attaching plate and a staple plate, said plates having screw openings and respectively corresponding in size and shape with the fixed and movable members of the hasp and being adapted to be covered thereby, the attaching plate being also provided with a flange at its lower side to engage one side of the fixed member of the hasp, and a pivot element arranged centrally of the fixed member and

the attaching plate, and securing said relatively fixed member permanently to the attaching plate and permitting said relatively fixed member to be turned to upright position to uncover the screw openings of the attaching plate. 15

In testimony whereof I affix my signature in presence of two witnesses.

FRED T. HARRIGAN.
